(57) **CLAIM**

The ornamental design for a body stretching bar, as shown and described.

DESCRIPTION

FIG. 1 is a perspective view of the body stretching bar;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is an additional perspective view of the body stretching bar in a typical environment.

The broken lines of FIG. 8 depict environment and form no part of the claimed design.

The claimed design is shown with a symbolic break in its length. The appearance of any portion of the article between the break lines forms no part of the claimed design.
